UNITED STATES PATENT OFFICE.

FRANZ KARL SCHNEIDER, OF PHILADELPHIA, PENNSYLVANIA.

INTERCHANGEABLE-TOOTH SEGMENT GEAR.

Application filed November 7, 1924. Serial No. 748,396.

To all whom it may concern:

Be it known that I, FRANZ KARL SCHNEIDER, a citizen of the United States, residing in Philadelphia, Pennsylvania, have invented 5 certain Improvements in Interchangeable-Tooth Segment Gears, of which the following is a specification.

One object of my invention is to provide an improved interchangeable inserted tooth 10 segment gear which will be of particular advantage when used in lieu of the driving shell gear on the head motions of looms or in other capacities where it is required to impart intermittent motion, either rotary or 15 linear.

In transmitting intermittent motion by means of a toothed segment wheel, it is well known that the end tooth on the lead side is subjected to considerably more wear and 20 strain than any other tooth on the gear; this being due to the impact brought to bear on said end tooth by starting the driven gear or rack into motion. It is obvious therefore that the life of the segment gear is commensurate to the length of time that the lead tooth can resist the continual shock.

I have found that the life of such a gear may be greatly prolonged by the introduction, in a particular manner, of interchangeable inserted teeth. When the lead tooth of 30 this latter mentioned type of gear begins to show signs of wear, it can be easily removed and interchanged with any other tooth on the wheel.

35 This process may be repeated as often as the number of teeth on the segment, after which all the teeth may be discarded in favor of an entirely new set.

When my improved segment gear is employed in the head motion of a loom, it replaces the chilled cast iron shell gear which is now in general use. In such capacity my improved gear has the added advantage of offering a quick and easy method of repairing or replacing a broken or worn tooth 40 without removing the entire gear from the loom. This advantage is recognized as an important factor to anyone skilled in the art of weaving since it avoids the possibility of 45 destroying the timing of loom head motion; it being well known that even a slight movement of the actuating gear out of its original set position will work havoc with the loom and require considerable time to restore the 50 parts to their proper weaving positions.

The above object and other advantageous

ends which will be set forth hereinafter, I attain in the following manner, reference being had to the accompanying drawing in which

60 Figure 1 is a longitudinal elevation, partly in central vertical section, showing an intermittent segment gear made in accordance with my invention,

Figure 2 is a transverse elevation of the 65 same, partly in section,

Figure 3 is an enlarged fragmentary section taken on the line 3—3 of Figure 2,

Figure 4 is an enlarged fragmentary section taken on the line 4—4 of Figure 1, and 70

Figure 5 is an enlarged fragmentary section taken on the line 5—5 of Figure 1.

Referring to the drawing, my invention includes a main shell 6 having an elongated body portion 7 of arcuate segmental cross 75 section. This body portion has two collars 8 and 9 at its opposite ends for allowing the device to be secured to the driving shaft; the collar 8 being provided with a set screw 10 for this latter mentioned purpose. Thus the 80 shaft will pass through the collars and under the body portion 7 with the latter part surrounding the shaft at positions between the collars 8 and 9.

The outer part of the body portion 7 has 85 a series of grooves 11, the grooves extending lengthwise and allowing teeth 12 to be freely inserted therein. The body portion 7 is also grooved transversely, at positions spaced apart, to provide arcuate channels 13. These 90 channels extend from the end surface 14 to the end surface 15 of the body portion and provide pockets for arcuate tie rods 16. The teeth 12 have holes 17 through which the tie rods 16 freely pass, as clearly shown in Figures 95 3 and 4 of the drawing. Clips 18 and 19 respectively engage the end surfaces 14 and 15 of the body portion 7, said clips having angularly extending flanges 20 which embrace the inner surface of the body portion 100 7, as clearly shown in Figures 1 and 2. The clips 18 and 19, at positions registering with the channels 13, have holes through which opposite end portions of the tie rods 16 extend. These end portions of the tie rods are 105 screw threaded and provided with nuts 21 and 22 which engage the outer surfaces of the clips and hold them in embracing contact with the body portion 7.

It is obvious that the parts of the structure, when in the position as above described, will hold the teeth 12 in position

2
within the grooves 11. Furthermore, when it is desired to remove or interchange any of the teeth, it is merely necessary to remove the nuts on one side of the device to allow 5 the tie rods to be withdrawn from one or more of the teeth of the series, after which the teeth may be interchanged or replaced and the tie rods can again be moved into their securing positions and the nuts again 10 applied thereto. By having the channels 13 and tie rods 16 positioned in planes between the collars 8 and 9 working room is provided and it is an easy matter to slide the tie rods out of securing position with the teeth and 15 again slide them back into their operative clamping positions. It is further obvious that this can be done quickly and easily without disturbing the position of the collars on the shaft.

20 It will be noted that in the particular embodiment of my invention as illustrated in the drawing, I have illustrated each of the teeth provided with three holes 17, one of said holes in each tooth being located in the 25 middle of the length, while the other two holes are spaced equal distances from the ends. In view of this arrangement of the holes 17 and the corresponding locations of the channels 13, it is obvious that if a tooth 30 becomes worn on one side, the tooth can be removed and turned around lengthwise and reinserted and in this manner new portions of the teeth can be presented for wear.

In order to decrease the necessity of frequently changing the teeth about, they may be case hardened, thus also increasing their life to exceed that of the chilled cast iron teeth above referred to.

Having thus described my invention what 40 I claim as new and desire to secure by Letters Patent is:

1. In a gear device, an arcuate body portion having a transversely extending channel; a series of teeth independent of said 45 body portion and being arranged transversely to said channel; and a tie rod positioned within said channel and having holding engagement with said teeth.

2. In a gear device, an arcuate body portion having a transversely extending arcuate channel; a series of teeth independent

of said body portion and being arranged transversely to said channel; and a tie rod positioned within said channel and extending through said teeth.

3. In a gear device, an arcuate segmental body portion having longitudinally extending grooves in its outer surface; teeth removably fitting said grooves, said body portion having a transversely extending arcuate channel in its outer surface; and a tie rod fitting within said channel and adjustably secured to the end surfaces of said segmental body portion.

4. In a gear device, an arcuate segmental body portion having longitudinally extending grooves in its outer surface; teeth removably fitting said grooves, said body portion having a transversely extending arcuate channel in its outer surface; clips embracing the end surfaces of said segmental body portion; and a tie rod within said channel and extending through said teeth, said tie rod having a clamping portion adapted to engage said clips.

5. In a gear device, a shell including an arcuate segmental body portion having collars at its opposite ends spaced apart, the outer surface of said body portion being grooved longitudinally; a series of teeth removably fitting said grooves, said body portion having a transversely extending arcuate channel; and an arcuate tie rod fitting within said channel and extending through said teeth, said tie rod being removably secured to said body portion.

6. In a gear device, a body portion of arcuate segmental cross section; a series of teeth arranged around said body portion and being independent thereof; clips engaging the ends of said body portion and having flanges embracing an inner surface thereof; and a tie rod extending through said teeth and in clamping engagement with said clips.

In testimony whereof, I have signed my name to this specification, in the presence of two subscribing witnesses.

FRANZ KARL SCHNEIDER.
